UNITED STATES PATENT OFFICE.

ROBERT WILHELM MAX NITZSCHE, OF OBERCARSDORF, GERMANY.

METHOD OF MAKING PRINTING-FORMS WITH FINE SCREEN FOR STEREOTYPE-WORK.

1,245,370.

Specification of Letters Patent.

Patented Nov. 6, 1917.

No Drawing.

Application filed December 22, 1916. Serial No. 138,524.

To all whom it may concern:

Be it known that I, ROBERT WILHELM MAX NITZSCHE, residing at Obercarsdorf, in the kingdom of Saxony, German Empire, have invented certain new and useful Improvements in Methods of Making Printing-Forms with Fine Screen for Stereotype-Work, of which the following is a specification.

10 The reason why stereotype casts of screened printing forms, in particular half-tone blocks with fine screen, have not been heretofore obtained in a satisfactory manner, lies in the fact that the unpressed matrix boards 15 which, as known, are obtained by couching several layers of but little sized paper pulp onto each other, will naturally have a coarse and rough surface, which in consequence of the unavoidable imprint of the felt will 20 have an uneven and irregular surface. These irregularities of the surface are caused by an irregular distribution of the pulp, or, in other words, an irregular density at the various points, so that when the block is im- 25 pressed onto such board, it will meet, at different points, a different resistance and a different degree of compression. By such denser and less dense parts lying next to each other of various expanse, the reprint of the 30 surfaces which, in the block have an even tone, will become cloudy. Some, closely limited denser parts will even result in local defects in the print. It is obvious that in im- 35 pressing the block not only the irregularities of the outer surface but also such of the lower layers will come into effect.

This fact alone proves that a coating of the one side only, the upper side, with a paste of chalk or baryta will not afford a perfect 40 remedy. But such a coating even has the disadvantage, that when the block is im- 45 pressed, particles of such coating will be cracked off or will be locked in the fine recesses of the screened surface and be torn off when the block is removed, so that defective 50 spots are caused in the stereotype form, and the block is soiled for a later impression. Only by an extremely careful preparation and dressing of the matrix board by expen- 55 sive, tedious and careful manual labor it was possible to obtain by the said method casts which gave satisfaction.

Calandering the boards would be quite unsuitable, as this would impair the impressi- 55 bility of the board. But even if this were not the case, the irregularities would be re-

moved outwardly only, or, in other words, be driven inward, so that the density of the board and in consequence thereof its impressibility would be varied at different points. 60 For the same reasons it is of no avail to cover a soft pasteboard core with a smooth calandered paper covering.

Neither has the adoption of the Foudrinier machine brought any success, which machine turns out endless pasteboard webs and by the coöperation of the wire cloth with heated drying rolls, with smooth surfaces thereon, because the impressibility of the matrix boards produced by such method is 70 too small and the smoothness of the product is likewise an outward one only.

It has now been possible to satisfactorily solve the problem by grinding the matrix boards manufactured in the usual manner, 75 subsequently on both sides. By thus removing the superfluous material a smooth surface and at the same time the necessary uniformity in thickness and density is obtained; this latter so much easier and surely, as the 80 grinding means (the grains of the grinding medium) will, at the denser points, find a greater resistance and therefore act more severely.

This grinding is preferably performed in 85 several stages (for example rough-grinding, finishing, polishing) on an even or smooth surface by plane grinding disks or grinding rollers covered with glass, sand or emery cloth or paper. During the grinding opera- 90 tion preferably a motion in several directions is provided, or the material is repeatedly sent through the grinding machine in different directions, so as to avoid a parallel grind, resembling the appearance of a filed 95 surface.

As the treatment is a chip-removing process, it might be possible to substitute rapidly revolving steel edges for the grinding medium, at least for the rough-grinding process. 100

Although the present method originated in the intention to find a satisfactory stereotyping process for screened printing forms, it may also be employed with matrix boards which are intended for common stereotype 105 purposes, such as stereotyping letterpress and wood blocks (engravings)—and will, in such cases, render good services particularly in printing fine or delicate fonts or engravings.

I claim:

1. The art of producing stereotype matrix boards which consists in subjecting matrix

110

- boards composed of couched layers of lightly sized paper pulp to a surface grinding in different directions substantially as herein set forth.
- 5 2. The art of producing stereotype matrix boards which consists in subjecting matrix boards composed of couched layers of lightly sized paper pulp to a surface grinding in different directions in successive stages of rough 10 grinding, finishing and polishing substantially as herein set forth.

3. A matrix board for stereotype casts consisting of a multiplex sheet composed of united couched layers of pulp having a regular thickness and a polished ground surface. 15

In testimony whereof I affix my signature in presence of two witnesses.

ROBERT WILHELM MAX NITZSCHE.

Witnesses:

MARTA PICKEL,
BERT. A. BRAINE.
